UNITED STATES PATENT OFFICE.

CHARLES B. ANDREWS, OF HIGH BRIDGE, NEW JERSEY, ASSIGNOR TO TAYLOR-WHARTON IRON AND STEEL COMPANY, OF HIGH BRIDGE, NEW JERSEY, A CORPORATION OF NEW JERSEY.

FULLER-MILL PUSHER.

1,209,101.

Specification of Letters Patent. Patented Dec. 19, 1916.

Application filed November 12, 1914. Serial No. 871,644.

To all whom it may concern:

Be it known that I, CHARLES B. ANDREWS, a citizen of the United States, residing at High Bridge, in Hunterdon county, State of New Jersey, have invented the following described Improvements in Fuller-Mill Pushers.

The invention relates to grinding mills of the type wherein the grinding or crushing is performed by balls rolling on a ring under the impulsion of several pushers, and consists more particularly in a formation of the pushers whereby an improved action upon and of the balls is secured, as well as certain other advantages hereinafter made apparent.

In the accompanying drawings: Figure 1 is a vertical sectional view of so much of a mill of the type referred to, as is necessary for an understanding of the improvement; Fig. 2 is a perspective view on an enlarged scale, showing a pusher in contact with a ball as in the act of impelling it around the ring, the yoke arm being in section; Fig. 3 is a sectional plan view of the balls, ring, yoke and pushers, the mill being at rest; and Fig. 4 is a perspective view of one of the pusher elements removed.

The general construction and relation of the grinding ring 2, balls 3 and yoke 4, with its arms 5 mounted on a revolving shaft 6, are well known to the art and require no detailed explanation; and it is to be understood that, as regards the particular form and arrangement of parts of the mill, other than the pushers 7, the drawings are purely illustrative of the type of mill known in the trade as the "Fuller mill." The said pushers are massive metal bodies, preferably of specially hard and tough material, and are socketed for removable mounting on the ends of the radial arms 5, the sockets 8 extending from the inner face of each to within a short distance of the outer face and being square to conform to the shape of the arms, and the securing of the pushers on the arms being effected by pins 9 secured by cotter pins 10, all as usual.

In my improvement the active side faces 11 of the pushers, which contact with and impel the balls when the mill is in operation, are of special formation, being convex in horizontal section and approximately straight vertically, and for general purposes may be

regarded as substantially cylindrical, though a true circular curvature is not essential. Furthermore, the pushers are bilaterally symmetrical with respect to their sockets, each therefore possessing duplicate active faces, which are interchangeable one for the other by removing the pusher from the arm and replacing it in reversed position. In the outer portion of the pusher, an aperture 12, materially smaller than the socket and opening through the end face 13 thereof, facilitates this removal, which is often difficult owing to the product of the mill packing between the yoke arm and sides of the socket. This aperture, however, does not give rise to wear and looseness due to material working outward through the socket, between the sides of the same and the arms, because the said end face surrounding the aperture is sufficient to arrest the particles, which are thus allowed to collect and hold the pusher firm.

Owing to the formation of the active faces 11, the engagement of the pushers with the balls is a contact between two convex surfaces, with the effect that under the conditions of operation in these mills, the greatest opportunity is given to the balls to roll on the ring, thus improving the grinding action, which is dependent upon the rolling action, preserving their roundness and reducing the power necessary for driving, the results in these particulars being substantially better than with the ordinary pushers having concave active faces wherein the balls are likely at times to become gripped and pushed with a sliding instead of a rolling movement. At the same time the vertical disposition of the convex working faces of my pushers insures the propelling force acting at all times against the balls in a horizontal plane and permits them to remain in their course by their own considerable weight without any tendency on the part of the pushers to throw them upward. This remains true irrespective of wear, to which the yoke is naturally subject, since the cylindrical curved pushers, even though gradually lowered, always impel the balls horizontally. The pushers being alike on both sides may be reversed when their forward faces become unduly worn, and will then of course serve for a second period of use.

I claim:

1. In a grinding mill, a grinding ring and balls adapted to roll in contact therewith to crush the material, in combination with a yoke and pushers thereon between the balls 5 consisting of massive bodies formed with sockets whereby they are mounted fixedly on the ends of the yoke arms, said pushers having approximately vertical cylindrically convex impelling faces adapted at all times 10 to act horizontally upon the balls.
2. A pusher for a mill of the type described consisting of a massive metal body formed with a socket whereby it may be fixedly mounted on the end of an arm and 15 having an approximately vertical cylindrically curved impelling face.
3. In a grinding mill comprising a grinding ring, balls adapted to roll in contact therewith in order to crush the material, and a rotary yoke, pushers each having an angular socket extending outward from its inner face for the reception of an arm on the yoke and an opening of materially smaller diameter than the socket extending from the outer face of the pusher and opening through the end face of said socket. 20

In testimony whereof, I have signed this specification in the presence of two witnesses.

CHARLES B. ANDREWS.
